UNITED STATES PATENT OFFICE

CARL WEEKS, OF DES MOINES, IOWA, ASSIGNOR TO THE ARMAND COMPANY, OF DES MOINES, IOWA

MASSAGE IMPLEMENT

Application filed January 6, 1930. Serial No. 418,817.

The object of my invention is to provide a massage implement of simple, durable and comparatively inexpensive construction, so arranged and designed that by use of such 5 implement, the body massaged may receive such treatment as is ordinarily afforded by a "manual massage."

Still a further object is to provide a small implement, preferably formed of glass, having a tapered and curved exterior surface and one surface formed with a series of undulations so that the tapered and curved portions of the device may be engaged by the palm or fingers of the operator, with 15 the surface having the undulations therein arranged for contact with the body of the operator over the portions to be massaged.

Still a further object is to provide the undulations of such design and configuration as to actually impart to the portion of the body massaged the same effect as though the parts were manually massaged. The undulations upon the surface of the implement are so arranged as to be gradual and 25 without any sharp corners or other portions, which might interfere with complete and satisfactory use of the device.

Still a further object is to provide one end of the device comparatively small in 30 cross section, so that such end, which may be referred to as the sharpened end, is capable of being worked upon the eyelids and around the nose with the tendency to conform to the contour of the face.

35 A further object is to provide a hollow receptacle adapted to contain ice, cold water, or a refrigerant chemical of any suitable kind whereby the implement may remain in a "cold" state while being used.

40 Still a further object is to provide a modified form having on the small end, a rubber applicator or other pliable massage member which may conform more readily to the contour of the face during massaging operations.

This application is a continuation in part of application Serial Number 400,090, filed October 16, 1929.

With these and other objects in view, my 45 invention consists in the construction, ar-

rangement and combination of the various parts of my implement, whereby the objects contemplated are attained, as hereinafter more fully set forth, pointed out in my claims, and illustrated in the accompanying 55 drawings, in which:

Figure 1 is a perspective view of my device showing the series of undulations on the top surface thereof.

Figure 2 is a top plan view of the same. 60

Figure 3 is a side view showing the series of undulations formed upon the top surface of the device.

Figure 4 is a sectional view taken on the line 4-4 of Figure 1, illustrating the cross 65 sectional contour of the device.

Figure 5 is a side elevation with parts broken away and shown in section, of a modified form of construction of the small end of the massage implement.

Figure 6 is a sectional view on the line 6-6 of Figure 5.

Figure 7 is a perspective view of another modification of my implement.

Figure 8 is a perspective view of the closure element for the form of device shown in Figure 7. 75

Figure 9 is a sectional view through the hollow implement; and

Figure 10 is a sectional view taken on the line 10-10 of Figure 9. 80

My device may be made preferably of glass, although it will be understood that it may be made of any other substance, which will retain a smooth surface at all 85 times.

The device A includes what may be called a top surface 10, and curved side surfaces 12, and a bottom surface 14. The curved sides 12 and bottom 14 are adapted to be arranged in the palm of the hand of the operator with the fingers arranged near the sharpened end 16 of the device, while the blunt end 18 is received in the palm of the hand. 90

When the device is properly gripped, so that the hand of the operator extends around the sides and bottom, the top surface 10 is left for operation upon the parts of the body to be massaged. 95 100

For convenience in holding the implement, grooves 22 may be formed along the sides thereof into which the ends of the fingers of the operator may extend.

The top surface 10 is provided with a series of undulations or ribs and grooves 20. The ribs and grooves are of the so-called wave-like formation. There are no sharp edges or corners, which would tend to irritate the skin of the operator when the implement is used upon the face or other tender parts of the body.

In Figures 5 and 6, I illustrate a modified form of construction in which the small end 16^a of the implement is made of rubber, rather than formed of the material of the body of the implement.

The body portion of the implement may be provided with a prong 24 preferably of angular construction, as shown in Figure 6, and provided with an enlarged head 26. This prong snugly fits in the pliable end 16^a of the applicator, which may be of rubber or other suitable material.

It is quite important that the entire implement be tapered from the blunt end towards the sharp end, that is from the end 18 towards the end 16, as clearly illustrated in Figure 2 of the drawings.

By preferably forming the device from glass, it gives to the face or parts of the body massaged, the same effect as though ice were used for massage purposes. The device further may be chilled in cold water before using, and glass substance will remain cold a comparatively long time, and thus the device may be used with desired results.

In the practical use of my device, the ordinary massage cream is placed over the parts of the body to be massaged, preferably the face and neck. The top side with its wave-like formation is then moved over the parts with the massage cream thereon. The series of undulations will give to the face or parts massaged the same effect as though a manual massage was being given.

The sharpened end 16 of the device may be moved in and around the nose, as well as upon the eyelids and in and around other parts of the head of such irregular contour, where it is ordinarily inconvenient to properly massage the same.

The implement may be made hollow as shown in Figure 9 of the drawings. The hollow receptacle is provided with a mouth 30 adapted to be sealed by a closure element 32 formed integral with the applicator 34. In this form of device refrigerant of any suitable kind can be inserted through the mouth 30 and thereafter the closure 32 placed in position. The device will then remain cold for quite some time while in use. It will, of course, be understood that other forms of closure elements might be

used efficiently to accomplish the same result.

One of the principal advantages of my device resides in the fact that it is so shaped and so arranged that practically any ordinary massaged portion of the body can be worked upon with my device.

My device has been in actual use and produces a very desired and beneficial result to the parts massaged.

When the form of device shown in Figures 5 and 6 is used, the pliable applicator 16^a conforms somewhat better to the contour of the face and provides a better massaging action.

The smooth side of my device can likewise be used to "chill" the face of the user. It will be understood that my massage implement is capable of meeting all conditions of use and therefore very desirable.

Some changes may be made in the arrangement and construction of the parts of my massage implement, without departing from the essential features and purposes of my invention, and it is my intention to cover by my claims, any modified forms of construction, or use of mechanical equivalents, which may be reasonably included within their scope.

I claim as my invention:

1. A massage implement having curved sides and a bottom, with a top surface provided with a series of undulations, and a pliable applicator mounted on one end of said implement.

2. A massage implement having curved sides and a bottom, with a top surface provided with a series of undulations, said implement being hollow and having a mouth whereby a refrigerant element may be placed within said implement and means for sealing said mouth, said last means being pliable and serving as an applicator.

3. A massage implement substantially as shown and substantially longer than it is wide, and longer than it is thick and tapered slightly and uniformly and symmetrically from end to end, and both laterally and from top to bottom, said implement having one comparatively large rounded end and one comparatively small rounded end and a rounded bottom and an undulated top, and having a cross-section with a curved bottom, outwardly and upwardly tapered sides, and a straight top, with its side adjacent to its top surface free from undulations and provided with lengthwise finger-receiving grooves spaced from its top and bottom.

Des Moines, Iowa, December 18, 1929.
CARL WEEKS.
